CLAIM

We claim the ornamental design for a knife, as shown and described.

DESCRIPTION

FIG. 1 is a perspective view of a knife according to the new design; and,

FIG. 2 is a right side view of the knife shown in FIG. 1.;

FIG. 3 is a left side view of the knife shown in FIG. 1.;

FIG. 4 is a top view of the knife shown in FIG. 1.;

FIG. 5 is a bottom view of the knife shown in FIG. 1.;

FIG. 6 is a front view of the knife shown in FIG. 1.;

FIG. 7 is a rear view of the knife shown in FIG. 1. Features shown in broken lines form no part of the claimed design.

1 Claim, 3 Drawing Sheets(56)
